United States Patent Office

Des. 177,095
Patented Mar. 13, 1956

177,095

TEXTILE FABRIC

William Edward Holt, Jr., Philadelphia, Pa., assignor to E. W. Twitchell, Inc., Philadelphia, Pa., a corporation of Pennsylvania

Application October 13, 1955, Serial No. 38,343

Term of patent 3½ years

(Cl. D92—1)

The single figure is a face view of a textile fabric showing my new design.

I claim:

The ornamental design for textile fabric, substantially as shown.
